EDGE BINDER FOR FURNITURE TOP SURFACING MATERIAL

James R. Clark, Rochester, N. Y., assignor to
Yawman & Erbe Mfg. Co., Rochester, N. Y., a
corporation of New York

Application August 29, 1927, Serial No. 216,284

5 Claims. (Cl. 311—107)

My invention is chiefly concerned with an improved construction of binding strip for dressing and protecting the edge of a sheet of linoleum or other surfacing material as employed on metal furniture tops and cabinets, wood or metal counter, stair treads, and the like.

Preferably my improved binding strip construction employs a binding strip itself of L- or J-shaped cross-section, the major leg being inserted in a marginal recess or slot which may conveniently be formed between the under side of the top plate and the upper side of a clamping strip secured immediately beneath the top plate and pinching the binding strip between it and the top plate. The binding strip is thus held in place under heavy friction, and by friction alone, thereby eliminating the use of nuts and bolts, screws, rivets, punches, etc., for its securing. The binding can be applied without removing the top or otherwise dismantling the article to be covered. And by applying the binding strip after the linoleum is laid, I simplify the problem of trimming the edges of the linoleum. This materially facilitates its application, not only cutting down labor cost in the factory, but making it convenient for application by workmen on the job.

A trimness of appearance effected by a narrow exposure of the binding strip free from any exposed rivets, bolts or the like is another possible advantage of my invention.

My binding strip, being held by friction, may be withdrawn slightly if necessary to relieve puckering of the linoleum, should it swell in damp weather. When the linoleum again contracts, the binding strip can be driven back inwardly to maintain a tight fit against the edge of the linoleum. Also, if the linoleum is not cut with a perfectly straight edge my binding strip is sufficiently flexible in itself and in its securing to the top plate, to permit its conforming itself to the edge of the linoleum and thereby avoid the untidy appearance of dirt-collecting crevices. My binding strip may similarly easily be withdrawn without the necessity of dismantling the top in case the linoleum is to be renewed or remounted.

As a result of some of these advantages, I am enabled to employ a new system of marketing batteries of filing cabinets, counter units, or the like—a system wherein the dealer may stock an assortment of units, a roll of linoleum and a minimum variety of binding strips. In fact, the binding strips preferably are in only two varieties: a notched strip of predetermined length, and a more

or less continuous unnoticed strip. The binding may readily be applied by the dealer to installations without delay in awaiting special factory work on the binding devices. This elimination of special work considerably lessens the cost to the consumer and makes possible immediate deliveries and installations.

A further object of my invention is the design of a top construction for a filing cabinet, desk, or the like which is adapted at any time to the reception of a linoleum-top edged with my binding strip, but which presents a neat and practical appearance if used without the linoleum and binding strip.

Another object of my invention is an improved furniture top construction, and especially a construction permitting a ready and accurate alignment of the tops for a battery of juxtaposed units, so that especially when a continuous sheet of linoleum or other surfacing material is applied to surface a plurality of adjacent tops, no objectionable joint will show through on the top of the linoleum. This latter end I effect by use of an alining strip entering opposed recesses in the adjacent upper edges of the tops of the adjoining units. Preferably these recesses are the same recesses in which the binding strips would otherwise be clamped.

The foregoing and other objects, features and advantages of my invention are set forth in the following description of specific embodiments thereof and in the accompanying drawings wherein:

Figure 1 is a perspective view of a battery of three filing cabinets provided with a unitary linoleum top secured by the binding strip construction of my invention;

Figure 2 is a fragmentary transverse vertical section taken on the line 2—2 of Figure 1, the cross-hatching being eliminated on the section parts for clarity;

Figure 3 is an enlarged corner section similar to that at the left-hand side of Figure 2 but upon an enlarged scale and without the linoleum covering and without the binding strip;

Figure 4 is a view similar to Figure 3 but showing the linoleum and binding strip applied;

Figure 5 is a plan view of the battery of filing cabinets shown in Figure 1 and illustrating the manner of application of the binding strips;

Figure 6 is a plan view of one of the binding strips properly notched and cut to embrace the end and part of the sides of a filing cabinet;

Figure 7 is a fragmentary perspective showing the top of a battery of filing cabinets such as shown in Figure 1 but before application of the

- linoleum top covering and binding strip, and broken away to reveal the transverse cross-section and especially to show the use of an alining strip;
- 5 Figure 8 shows a construction similar to Figure 4 but adapted specifically for a metal desk top construction the downwardly depending flange being arranged to simulate the thickness of a desk top;
- 10 Figure 9 is a view similar to Figure 8 but illustrating a variation in the form of the binding strip and incorporating a more or less positive block for the binding strip by a deformation effected by a center punch or the like;
- 15 Figures 10 and 11 illustrate another variation of positive locking means incorporating spaced alined holes in the spaced plates between which the binding strip enters;
- 20 Figures 12 and 13 illustrate another modification of my corner construction and one which is especially adapted for binding strips for covering material laid on a wooden counter, wooden desk top, stair tread or the like, Figure 12 showing the construction before, and Figure 13 after, the application of the linoleum and the binding strip;
- 25 Figure 14 is a fragmentary perspective view of the construction of Figures 12 and 13 showing the use of an alining strip across a butt joint formed in the clamping strips;
- 30 Figure 15 is a view similar to Figure 13 but showing an alternative construction.
- As the application of a linoleum or other surfacing material top, and a binding strip edge construction therefor, on a single or a battery of filing cabinets or other counter height units constitutes one of the most important applications of my invention, I have chosen to show it as applied to a battery of counter height filing cabinets, although of course it will be appreciated that my invention is susceptible of numerous other applications not only in the particular forms and structures shown, but in many variations as well.
- The battery of filing cabinets shown in Figure 1, comprises three units 20 secured together in any suitable way such as by the usual clamping bolts passing through juxtaposed side walls. Each unit carries at its upper end a cap or sub-top 21 having integral depending lateral flanges 22 on each of the four sides. The upper ends 23 of the side walls 23 are suitably set back as at 24 (Fig. 2) to permit the cap 21 fitting snugly over the upper end of the side walls with the exterior of the flanges 22 in alinement with the exterior of the exposed side walls 23. The cap or sub-top 21 has a central elevated panel leaving a depressed marginal frame portion 25. An incidental result of this paneled effect is that it serves to give greater rigidity to the top. A super-top or upper top plate 26 lies upon, and is preferably spot-welded to, the sub-top 21 with its edges overlying the marginal depressed regions 25 of the sub-top leaving a marginal recess 27 therebetween. The outer edges of the top plate 26 preferably come out flush with the lateral walls of the units, that is flush with the outer surfaces of the depending flanges 22. For the sake of clarity in the drawings the size of the recess 27 in Figure 3 for example has been exaggerated, but it will be understood that in practice although the slot or recess is there, the plates forming the recess are preferably sprung together slightly so that the actual space is less and almost unnoticed by casual glance. I make this point because I consider it quite advantageous to have the recess 27 as inconspicuous as possible so that the cabinet units
- 5 may be used without linoleum tops or binding strips and still present a neat and trim appearance. This makes it entirely feasible for a manufacturer to standardize on one type of cabinet top construction which may be used either with or without a covering material such as linoleum. As a result the dealer's stock can be reduced and also the purchaser may at any subsequent time use his units in an arrangement where a linoleum top becomes desirable. And even though a particular purchaser may never want to use a top covering on his cabinets, still their resale value is increased because of the greater range of utility to subsequent purchasers.
- 10 I shall next describe the application of a linoleum top, and of the binding strip for the edge thereof. While I illustrate and describe a sheet of linoleum for the top covering, it is to be understood that my invention is not to be construed as specifically limited to linoleum. Any 15 other generally similar sheet material could satisfactorily be substituted. Or rubber tiles in small squares for example could be used. Also strips of contrasting colors of linoleum can be used to incorporate a design in the top. If the appearance 20 of wood is desirable, a panel of wood veneer could be used instead of the linoleum. Similarly ceramic or other clay tiles could be used and protected at their edges by the same structure of binding strip. It would even be practicable to use my 25 binding strip for securing a glass top on the cabinets, protecting its edges against chipping and holding the glass against displacement. The foregoing, however, is not an exhaustive catalog 30 of the available substitutions, but merely a suggestion as to the wide scope of uses to which my invention may be applied.
- 35 In those instances where a battery of counter height units are to be set together—and whether or not they are to be covered with the linoleum—40 it is desirable, because of the unevenness of the floor or inaccuracies in uniformity of production of the cabinets, to employ some means of positively alining the top surfaces where they juxtapose. An alining strip 28 which consists merely 45 in a flat strip of sheet metal about an inch wide and of a length about an inch less than the depth of the unit, is inserted in the respective opposed recesses 27 along the contiguous upper edges of two juxtaposed units as shown in Figure 2 and 50 more clearly in the perspective of Figure 7. The method of inserting this aligning strip 28 is preferably to drive it laterally into the recess on one of the units, and then bring the two units together with the outer lateral edge of the strip entering 55 the opposed recess of the other unit, and then pushing or hammering the two units together. Although the alining strip be formed from relatively thin metal, its entire area is tightly clamped in either one or the other of the opposed recesses 60 leaving insufficient region for any appreciable flexure. The result therefore is to bring the adjacent edges of the two top plates 26 into a flush butt joint. This joint may thus be made so inconspicuous as to present the practical appearance 65 and feel of a continuous sheet metal top, in the event that no linoleum cover is applied. If a linoleum cover is applied the advantage of this positively alined joint is to preclude the "wearing up" of a ridge on the upper surface of the lino- 70 leum.
- 75 In the application of the linoleum, a sheet of linoleum 29 is preferably cut approximately to the size required. It is then cemented to the upper surface of the top plates 26, and, as is the usual 75

practice, weighted down with sand bags and allowed to set over night. After the cement has sufficiently set, and if the linoleum has not been cut accurately to the perimeter of the top plates 26, it may be trimmed with a knife, using the peripheral top plates 26 as guides. This, it will be observed, is an advantage which cannot be obtained when the linoleum has to be applied after the binding bead is put in place. One can readily appreciate that it is much simpler to trim the linoleum to the correct size from a roll of stock. And by the use of my method it is not necessary, even though the sheet could be cut to the correct size, to take so much pains in correctly positioning the sheet on the top plates before the cement starts to harden.

The binding strip 30 itself is of an angle cross-section, including a horizontal flange 31 and a vertical flange 32. The horizontal flange 31 is adapted to be inserted in the recess or slot 27 and driven thereto. The flange 31 is of slightly greater thickness than the normal height of the slot 27, so that in entering it springs apart the plates defining the recess 27. This serves to hold the strip under heavy friction, preferably requiring the use of a hammer to effect its entrance. The upper and inner edge of the flange 32 of the binding strip is preferably turned backwardly into something of a knife edge 32' which imbeds itself in the edge of the linoleum. The flange 32 does not come to quite as high a level as the top surface of the linoleum, so that there is no opportunity for anything to catch behind the knife edge 32' and tend to pull the binding strip 30 out of the recess 27. On the other hand there is insufficient exposure of the lateral edge of the linoleum to permit of its being damaged or scuffed up. Preferably the binding strip does not have to be driven in quite far enough in the inner side 40 of the vertical flange 32 to strike the lateral edge of the top plate 26. This makes it possible to drive the binding strip in a little farther should the linoleum subsequently tend to shrink slightly.

The binding strip 32 will project slightly beyond the plane of the lateral wall of the unit, in the arrangement shown in Figure 4. This projection is not objectionable, for it gives a desirable effect of trimness. If for any reason it is desired to eliminate the overhanging of the alining strip, this may be effected by cutting a little off the marginal edges of the top plate 26. I prefer not to do this however because, since the units will often be used without linoleum tops or binding strips, it is advantageous to preserve a neater appearance for the upper corner of the units by bringing the top plate 26 out flush with the lateral walls.

In order to reduce the amount of special work required in the installation of a linoleum top unit or battery of units, and to reduce the variety of stock required to be carried by a dealer, I prefer to standardize on a unit 31' of binding strip such as shown in Figure 6. The overall length of this strip is equal to the depth of a cabinet unit plus its width. At a distance inwardly from each end of the strip equal to half the width of the cabinet unit, I provide a V-shaped notch 33 leaving at the apex of the notch, only the vertical flange 32. To apply this standard unit binding strip 31', the intermediary reach between the notches 33 is aligned along a side edge of the cabinet and pounded into the recess 27, leaving the outer reaches of the strip projecting beyond the front and rear edges. Each of these projecting reaches is then bent toward the adjacent end

edge of the cabinet and hammered into the corresponding recess 27. The horizontal flanges 31, which had been notched to 90° at 33, then form miter joints. The end reaches of the unit strip 31 extend to the mathematical midpoint 5 of the respective cabinet unit. Another standard unit binding strip 31' is similarly applied to the side of the cabinet unit at the other end of the linoleum. Referring to Figure 5, where the linoleum top covers three units, this leaves, at each 10 side, a gap equal to twice the width of the cabinet unit. Binding strips of the requisite length for filling in these gaps are then cut from more or less continuous lengths of binding strip, and are driven into the respective recesses 27, as 15 shown at the upper edge of Figure 5. This done, the application of the linoleum top and binding strip is completed and with practically no waste of material and in a minimum of time. In the instance of a single unit to be covered, the second 20 standard length notched binding strip 31' would nicely complete the binding of the entire periphery.

The outstanding advantages which I again wish to point out are that the work can be installed by a relatively unskilled workman at the purchaser's file room or office, and without the necessity of making up anything first in the dealer's work rooms, or at the manufacturer's factory. No special work or parts are required 25 no matter how big or irregular in shape the linoleum top may be. If an angular cabinet unit is used to carry the cabinet around the corner to accommodate it to some physical irregularity in the room or building where installed, the binding 30 strip will readily follow it, notches similar to those shown at 33 in Figure 6 being employed if the binding strip must make abrupt turns. If the dealer has the required stock of cabinet units 35 on hand, the only delay attendant to an installation is the over night delay waiting for the linoleum cement to set. The application of the binding strip itself requires a negligible amount 40 of time.

Sometimes the linoleum will expand in damp 45 weather, or under other adverse conditions, forming puckers or rolls. This condition can readily be relieved when my binding strip construction is used, for the binding strip along the affected region can be withdrawn slightly, by the aid of a 50 screw driver or a pair of pliers, sufficiently to allow the linoleum to resume an even surface. If the linoleum subsequently contracts, the binding strip can readily be made to follow it by a few taps with a hammer. Similarly, if the linoleum is to be renewed, or to be recemented, the binding strips can be pulled out and used for a second time without impairing their effectiveness or appearance. If the binding strip suffers an injury at some region which permanently 55 deforms it and gives it an unsightly appearance, it is not necessary to remove the entire binding strip, or loosen the cemented linoleum, or send to the manufacturer's factory for a substitute binding strip cut to size, for the dealer can readily pull out the binding strip for a little distance, cut out the damaged portion, and substitute a new length, cut to size from his stock strip material,—all without any considerable expense or delay or impairment of the attractiveness of the 60 binding.

In applying my invention to the top of a steel desk, I prefer to use a modified construction such as shown in Figure 8. Here the major or central area of the top does not consist of two thick- 75

- nesses of sheet metal, but only of the top plate 26. The depending lateral flange instead of being formed from a sub-top is applied as a marginal strip, spot-welded to the top plate 26 and mitered at the corners. This strip which I have designated generally in Figure 8 as 35, consists of a horizontal flange 36 immediately underlying the top plate 26 and spot-welded thereto, a downwardly offset horizontal portion 37 toward the outer edge, forming between it and the top plate 26 the recess 27, a deep down-turned vertical flange 38 simulating the thickness of the desk top, and a backwardly or rearwardly turned horizontal flange 39 simulating the under surface of the thickness of a desk top. The rebent flange 39 extends to the side wall 40 of the desk.
- A modified form of binding strip is illustrated in Figure 9 where the binding strip is given a greater vertical exposure by including a region 41 of double thickness embracing the upper edge of the flange 38. In Figure 9 I have also illustrated a practicable way of positively locking the binding strip in the recess 27. This is accomplished by a conical deformation 42 made with a center punch or other suitable tool which effects an interlocking deformation of the superposed layers of metal. Such a deformation does not necessarily wholly prevent the subsequent withdrawal of the binding strip but makes it much more difficult than as though it were held with friction alone. It is to be observed, however, that although this more or less positive locking means is employed, it does not necessitate a predetermining of the extent to which the binding strip will be driven into the recess 27, but permits the margin of the linoleum to determine this. In Figures 10 and 11, I have shown another method of more positively locking the binding strip in place. In this instance the depressed horizontal flange 37 of the rail member 35 and the top plate 26 thereabove are provided at spaced intervals with alined holes 43. After the binding strip is driven in place, a suitable punching tool may be inserted in the hole 43 from beneath the horizontal flange 37 and the binding strip, at the region exposed by the holes 43, deformed as shown in Figure 11 into the hole 43 in the top plate 26 to lock it against dislodgment. This punching may conveniently be done before the top structure is secured to the desk body. In the construction of Figures 10 and 11 also, it will be noted, the binding strip need not be driven any predetermined distance into the recess 27.
- While I have shown these auxiliary means for securing a more positive lock of the binding strip, I do not consider for most practical purposes, such a locking means as necessary. I have found that in practice a sufficient frictional clamping may be maintained to insure against an accidental dislodgment or withdrawal of the binding strip. As previously pointed out there is preferably no opportunity afforded for anything catching on the binding strip to effect its accidental withdrawal. And in any event it is driven in the recess with such a tight fit that it requires a definite effort to withdraw it.
- My invention is also adaptable to binding edge constructions where the linoleum instead of being applied to steel furniture, is applied to wooden furniture, wooden-top cabinets, wooden-top counters, table tops, wooden stair treads, and the like. As shown in Figure 12 the marginal edge of the wooden top or the like 50 has its upper and outer corner rabbeted as at 51 for

the reception of a clamping member 52, formed from a longitudinally rebent strip of metal providing closely spaced horizontal flanges with a recess 53 therebetween. The recess 53 is considerably longer than the flange 31 of the binding strip 30 which it receives (see Fig. 13).

At a distance outwardly from its inner or webbed end the clamping strip 52 is pierced by spaced alined holes for clamping screws 54, the heads of which are countersunk in the upper flange of the strip. The screws 54 are preferably turned down tightly enough to spring the upper flange toward the lower flange and thereby reduce the normal height of the recess 53. When the horizontal flange 31 of the binding strip is driven into the recess, it spreads the recess. In this way, to a certain extent, the frictional tension of the clamping strip can be predetermined by the tension applied by the clamping screws 54. However, the strips are preferably made with sufficient initial tension satisfactorily to hold the clamping strips under frictional tension so that even should the wood rot out or the screws otherwise lose their tension, the binding strips would not easily be pulled out of the recesses 53. The linoleum or other covering 55 in this instance is cemented directly to the top surface of the wooden top 50 and also to the top surface of the upper flange of the clamping strip 52, which in effect, forms a continuation of the top surface of the wood. In this instance also the linoleum may be cemented in place and trimmed with the clamping strip as a guide, before the clamping strip 30 is applied. Where the clamping strips are used on a counter for example, where because of the length of the counter, the strips cannot conveniently be continuous, they can be arranged with a butt joint as shown in Figure 14. An alining strip 46 entering part into one reach of clamping strip and partly into the other, and disposed at the back of the recess 53 can be used in conjunction with such a butt joint. In this case, if the spaced holes do not come in the right position, suitable holes can be drilled for the clamping screws 54 which will extend not only through the upper and lower flanges of the binding strip, but through the alining strip 46 as well. In Figure 15 I have shown a modified form of binding strip of an elongated G-shaped cross-section where the binding strip itself gives sufficient thickness to simulate the thickness of an overhanging top construction.

I claim:

1. An edge construction for furniture tops or the like comprising means presenting a top surface for the reception of a layer of linoleum cemented thereto and including a pair of vertically and resiliently spaced horizontal plates at its periphery forming a smooth-walled marginal recess, and a binding strip of angular cross-section having a horizontal flange entering and retained in said recess solely by friction and a vertical flange embracing the edge of the covering material,—the horizontal flange of the binding strip being operatively insertable in the recess after the linoleum is cemented in position on the top surface.

2. A combined cabinet unit comprising a group of equi-height cabinet units of rectangular plan having vertical lateral walls extending from top to bottom in substantially the planes of the respective edges of their tops and having horizontal marginal slots immediately beneath the tops of the several cabinet units, aligning strips between immediately adjacent cabinet units extending lat-

erally into each of the marginal slots along the juxtaposed edges of the respective units, a continuous layer of surfacing material covering the combined areas of the tops of the grouped cabinet units, and marginal binding strips engaging the edges of said surfacing material and retained within said marginal slots about the perimeter of the combined cabinet units.

3. A battery of juxtaposed sheet metal cabinet units presenting a combined top surface for the reception of a sheet of surfacing material each unit having a flat top plate and lateral sides extending from the bottom to the peripheral edges of the top in substantially the vertical planes thereof but leaving a peripheral horizontal slot immediately beneath the top plate for the reception of horizontal aligning plates along the juxtaposed edges of the units of the battery and for the reception of the attaching flanges of binding strips for the edges of the surfacing material along the perimeter of the battery.

4. An edging for top surface members of desks and the like comprising a top surface supporting element, a frame-like main edge member having a generally horizontal flange underhanging the said supporting element and an integral flange depending from the outer edge of the horizontal flange, the horizontal flange having an outer portion offset downwardly from the bottom surface

of the said supporting element and an inner portion secured to said element, and an edge strip along said surface member, said strip having an inwardly directed horizontal flange between said element and said offset flange portion, said flange of said strip contacting with and being secured in place solely by said downwardly offset portion and said element.

5. A furniture top comprising a metal supporting plate, a main metal frame supporting said plate, each side of said frame being composed of upper and lower substantially horizontal webs connected by a transverse web; each upper web comprising an inner portion engaged with and fixedly secured to the bottom of said plate and a resilient outer portion spaced downwardly from the bottom of said plate, and a generally L-shaped edge strip about said top, said strip having one of its legs disposed between the bottom of said plate and said outer portion of said upper web, said leg being of greater thickness than the unsprung distance between the bottom of said plate and said outer portion of said upper web whereby said leg will be tightly clamped by and between said plate and said outer portion of said upper web, the other leg of said strip extending upwardly and along the perimeter of said top.

JAMES R. CLARK.
